PARTITION CLIP

William Hueglan, Jr., Tenafly, N. J.

Application June 5, 1937, Serial No. 146,560

2 Claims. (Cl. 312—140.3)

This invention relates to a clip for mounting partitions in display trays or counters for forming compartments, such as are used, for example, in the display of small articles of merchandise in stores.

The counters are ordinarily formed of floor sections commonly called false bottoms, shams, platforms, cleats or trays, hereinafter called floor sections or shams. These floor sections or shams are supported upon a suitable base within an enclosing fence or rail, and for the purpose of exhibiting the merchandise in separate tray-like compartments they have been subdivided by partition walls mounted in various ways. In some cases, both longitudinal and transverse partition walls have been inserted between the floor sections to make compartments or trays of the same size as the floor sections. The more common practice, however, has been to have the floor sections extend from front to rear of the counter, with deep partition walls between them, and to subdivide these spaces transversely by shallow partition walls which are mounted on the surface of the floor sections by clips and extend across the floor sections between the projecting surfaces of the deep, fore and aft partition walls. Various type of clips for this purpose have been proposed and used, and an important object of the present invention is to provide a clip which may be firmly anchored in the floor to securely support and hold the partition, and which at the same time will permit the partitions to be assembled in a great variety of positions so that the user may readily form compartments or trays in a great variety of dimensions.

In general, the clip, according to my invention, comprises a base or partition-supporting member from which a plurality of ears project upward to engage the partition, and a plurality of anchorage feet project downward to engage the floor sections or shams. It will be understood that the floor sections or shams are provided with perforations or recesses at proper spacing to receive the anchorage feet. In a preferred form, the partition-engaging ears are two in number and are made resilient so as to permit the partition to be sprung into the space between them and resiliently held therein by friction, and the anchorage feet are two in number and are resilient so as to grip between them the material intervening between two perforations or recesses in the floor sections or shams. Further important details of construction and use will be apparent from the description of an embodiment

of the invention illustrated in the accompanying drawing, in which

Figure 1 is a perspective view, with parts in section, of a counter subdivided into compartments by partitions supported and held by clips 5 constructed in accordance with the present invention.

Figure 2 is a top plan view of the junction of two transverse partitions with a longitudinal partition mounted by clips according to the invention.

Figure 3 is a transverse vertical section taken on the line 3—3 of Figure 2.

Figure 4 is a longitudinal vertical section taken on the line 4—4 of Figure 3.

Figure 5 is a detail edge view of one of the clips.

Figure 6 is a plan view of a blank from which the clip may be formed, and

Figure 7 is a detail perspective view, with parts 20 in section, illustrating the construction of one of the floor sections by which the bottom of the tray may advantageously be formed for use in conjunction with the clips of the present invention.

Referring in detail to Figure 1, the floor boards 10 are mounted on strips or sills 11. Perforations or recesses 12 are spaced at constant intervals along each edge of the floor board section, and if the sill members 11 are secured under 30 these perforations or recesses 12, the sill members are preferably, though not necessarily, channeled or routed as at 13 to provide free space beneath the perforations 12. For certain purposes, as will be explained later, it is desirable that the line 35 of perforations 12 be spaced from the edge of the floor section 10 at a distance equal to half the distance between the perforations within the line. In accordance with the usual practice the floor sections may be covered with a layer of 40 felt, as indicated at 14.

The clip, as illustrated in detail in Figure 5, comprises a base portion 15, preferably of one single layer of sheet metal, from which a pair of resilient ears 16 project upward to engage a 45 partition 17, and from which a pair of feet 18 project downward to engage the floor material intervening between two of the perforations 12, as shown clearly in Figures 3 and 4. Figure 4 shows the clip anchored in two perforations of 50 the same floor section, whereas Figure 3 shows the clip anchored in two perforations in adjoining floor sections. By having the line of perforations 12 along each edge of a floor section spaced inward from the edge a distance equal to 55

one half of the space between perforations of the same line, the same clip may be inserted to support either a longitudinal partition, as illustrated in Figure 3, or a transverse partition, as 5 illustrated in Figure 4. When mounted as shown in Figure 3 the clip not only supports the partition, but also locks together the two adjoining floor sections. The channels 13 formed in the floor sills may advantageously be made somewhat 10 wider than the diameter of the floor perforations, so as to permit the anchorage feet 18 of the clip, when longer than the thickness of the floor board, to spring under the edge of the perforation to provide a more secure anchorage.

15 With reference to the details of the clip itself, it will be seen from Figure 6 that this may be stamped from a rectangular blank of sheet metal, practically without waste. All parts of the clip may be integral. The base portion 15 extends 20 along the entire width of each ear 16 and projects beyond the planes of the ears to the lines 19, from which the feet 18 are bent downward. This design or construction provides a clip of a high degree of stability, strongly resisting any tendency to rock, tilt or turn in any direction. The 25 ears 16 are turned upward approximately at right angles into two approximately parallel planes, whereas the feet 18 are turned downward approximately at right angles into two approximately parallel planes, the latter planes being more widely spaced and generally parallel to the 30 planes of the ears 16. The base 15 acts as a stop to arrest the clip as it is being inserted in the floor and hold it in true upright alignment, and 35 it furthermore provides a seat for the partition 17, which is to be embraced by the ears 16. While, in a sense, the ear portions 16 may be regarded as each comprising a pair of ears united at their outer or free ends, the invention in its 40 broader aspect is not strictly limited to their being thus united. In a broad sense, it is immaterial how many ears are employed, so long as they are at least two in number and are adapted to embrace between them the partition which 45 they are to support. On the other hand, a specific and preferred feature of the invention resides in the continuity of the metal across the outer top of each ear, since this construction establishes an inverted U-shaped brace or truss 50 in a plane at an angle to the plane of the base, and thus contributes to the rigidity of the base member against bending, and at the same time strengthens the engagement of the ears with the partition.

55 It will, of course, be understood that in manufacturing the clip, sheet metal of proper strength and thickness should be selected, according to the requirements of a particular use. Hardening or tempering to the required degree of resilience 60 may obviously be employed.

With reference to Figure 1, it will be quite apparent that the partitions extend longitudinally and transversely of the tray, and compartments of various dimensions and proportions may be formed by proper selection and location of the 5 various partition units. While I have illustrated the formation of the tray floor in sections or units, it is obvious that any other type of floor construction for such trays is equally adaptable to the use of the clip by arranging the anchorage 10 perforations or recesses in lines of any desired directions with proper spacing of the perforations to receive two anchorage feet of the clip wherever it may be desired to mount it. Ordinarily, two or more clips are employed for each partition, and these of course must be properly aligned with each other in order to receive the partition. The principle of having the anchorage feet of each clip 15 widely spaced, and engaging in two perforations instead of one, affords a very firm and positive 20 alignment of the partition-embracing ears of successive clips in the same line, and even makes perfectly feasible the use of a single clip on relatively short lengths of partition without fear of the partition being angularly displaced under 25 any ordinary conditions of use.

I claim:

1. A partitioned display counter equipment comprising in combination a floor member having a line of spaced recesses, and a partition-supporting clip mounted thereon, said clip having a floor-engaging base portion with a pair of partition-engaging ears bent upward from said base portion approximately at right angles thereto into approximately parallel relation to each other, 35 and a pair of resilient anchorage feet bent downward from said base portion into inclined relation to each other and spaced apart at their lower ends a distance slightly less than the space between two of the recesses in said floor member 40 to resiliently anchor the clip therein.

2. A partitioned display counter equipment comprising in combination a pair of separable floor members disposed adjacent to each other, each having a recess near its edge which adjoins the other, and a partition-supporting and floor section-locking clip mounted over the junction of said floor members, said clip having a floor-engaging base portion with a pair of partition-engaging ears bent upward approximately at right 45 angles from said base portion into approximately parallel relation to each other, and a pair of resilient anchorage feet bent downward approximately at right angles from said base portion but inclined toward each other and spaced apart a 50 distance slightly less than the space between a recess in one of said floor members and a recess in the adjacent floor member, to resiliently hold the adjacent floor members together.

WILLIAM HUEGLIN, JR. 60
